CONTROL APPARATUS

Ernest M. Miller, Minneapolis, Minn., assignor to
 Minneapolis-Honeywell Regulator Company,
 Minneapolis, Minn., a corporation of Delaware

Application April 28, 1930, Serial No. 448,011

17 Claims. (Cl. 158—28)

This invention relates to improvements in burner apparatus control means, in which the apparatus to be controlled includes a burner, combustion chamber, burner draft motor, ignition and fuel supply and control means. The control of this invention includes means whereby ignition of the fuel may be obtained; means whereby if flame is not produced when ignition and fuel is supplied the apparatus will cease to operate; means whereby ignition may be maintained for a predetermined length of time after production of flame, and then discontinued; means whereby ignition can be discontinued, but motor operation continued, until flame is extinguished either by a call for less heat and normal shut-down of the motor, or by flame or electrical failure; and means providing delayed re-ignition after a shut-down, no matter what the cause.

20 Features of the invention include specific as well as generic ideas of means.

Features and advantages of the invention will be set forth in the description of the drawing forming a part of this application, and in said drawing:

Figure 1 is a diagrammatic view illustrating the condition of the apparatus after activation on a call for heat;

Figure 2 represents the condition of the same system after flame has been produced, and before the ignition means is de-activated; and

Figure 3 represents the normal operating condition of the system after flame has been produced, and after ignition has been rendered inoperative.

The circuit arrangement of each figure is identical with that of every other, only the positions of the relays and contacts differ. The numerals have (in order to avoid confusing multiplication) been applied in any figure only to those parts of the circuit which are active, but any missing number can be easily found by reference to another figure (see description of the operation).

Referring to the drawing, a thermal safety switch is provided for rendering the entire apparatus inoperative at the end of a predetermined time if flame is not produced. This device includes a switch 6, and a heating coil which causes the switch to open in a well known manner at the end of a predetermined time. The device is made operative simultaneously with ignition. A room thermostat includes elements W, B, R. A time switch includes a bimetallic thermal element 12 controlling contacts 11 and 13, along with the heating element 56. This time switch functions when sufficiently cold to close the contact 11 which is in the starting circuit to coil 16 of relay No. 1. The starting circuit includes element 12, in series with switch 6, and with coil 15. Element 12 is here shown as a bimetallic arm, utilized

as a conductor. Other equivalent devices may be used. This switch also functions to close a holding circuit for relay No. 1, which includes coils 15—16 and additionally functions when sufficiently hot and at the end of a predetermined time to open both contacts 11—13 (respectively starting and holding contacts for relay No. 1) and cause them to remain open under the heating action of the coil (and after opening of relay No. 1) as long as the apparatus is operative. When there is a call for less heat by the room thermostat the whole device is rendered inoperative, and cannot be started until the time switch 12, as the result of a cooling action again closes the contact 11. Relay No. 1 controls its own holding contact 15 which contact is closed when the relay is energized, and also controls a contact 21 in the starting circuit of coil 58 of relay No. 2. Relay No. 1 when energized also closes contacts 22 and 23 respectively energizing ignition means and burner motor. Numeral 43 indicates the coil of relay No. 3 and this coil is energized when the contact 40 closes. This contact is thermally controlled, in a manner not shown, and is part of what is well known as a "pyrostat" or an instrument which closes its contact in response to production of flame at the burner, and usually placed in the stack. The function of relay No. 3 is to break the starting circuit to relay No. 1 and to complete a starting circuit to relay No. 2 on production of flame. Relay No. 2 is energized substantially simultaneously with the energization of relay No. 3.

Relay No. 2 controls contacts 60, 61 and 62. Contact 60 controls a holding circuit for relay No. 1 which does not include the heating coil 15 of the thermal safety switch. When contact 60 closes, coil 15 is therefore shunted out. Contact 61 is in the holding circuit for relay No. 2, and contact 62 is a second contact which controls the motor and maintains it in operative condition, after opening of relay No. 1 and contacts 22—23 controlled thereby. Suitable ignition means is indicated at 38 and a suitable burner motor at 34.

In the embodiment of the invention shown in the drawing, the function of No. 1 relay is to activate ignition and motor, establish a holding circuit for itself (which can be opened by either the thermal safety or time switch) and close a contact in the starting circuit for No. 2 relay. The function of No. 3 relay is, on production of flame, to close a contact which is in both starting and holding circuits for No. 2 relay, and to open a contact which is in the starting circuit for No. 1 relay. Energization of No. 2 relay causes heat to be delivered to coil 56 of the time switch, shunts out the coil 15 of the thermal safety switch, establishes a holding circuit for itself, and for relay No. 1 through the heating

coil of the time switch. The function of the time switch (when sufficiently cold) is to close the starting circuit for No. 1 relay, which when energized activates ignition and burner motor 5 (when the room thermostat is closed) and later, when sufficiently hot, breaks the holding circuit for No. 1 relay to render ignition inoperative.

Operation

- 10 Assuming a call for heat (see Figure 1) and closure of contacts B and W by R of the room thermostat. Relay No. 1 will be energized through the following circuit: secondary 4, conductor 5, switch 6, 7, W, B, 8, contact 9, 10, contact 11, thermal element of the time switch or its equivalent, contact 13, 14, heating coil 15 of the thermal safety switch, 17, coil 16 of relay No. 1, 17^a to the opposite side of the transformer 4. Energization of relay No. 1 results in the closure 15 of four contacts, to-wit: 20, 21, 22 and 23. Contact 21 is a holding contact for relay No. 1 and the holding circuit may be traced from the transformer 4, to R of the room thermostat, 24, 25, contact 20, 26, thermal element 12 of the time switch, contact 13, 14, and thence through heating coil 15, 17, relay coil 16, 17^a, to the opposite 20 side of the transformer 4. Contact 21 is in the starting circuit for relay No. 2 and is closed on closure of No. 1 relay. Contact 22 establishes a 25 circuit for the motor as follows: hot line 1, 30, 31, 22, 32, 33, motor 34, 35 to ground line 2. Contact 23 establishes a circuit for the ignition means as follows: line 1, 30, 36, 23, 37, ignition 38, 39 to ground line 2. After closure of relay No. 1 30 further operation of relays No. 1 and No. 2 is controlled through W—R of the thermostat. Contact 21 controlled by relay No. 1 is in the starting circuit for relay No. 2 and it is therefore seen that relay No. 2 can never close unless No. 40 1 relay is energized.

Ignition means and the burner motor are now operative, and if combustion does not take place at the end of a predetermined time safety switch 45 will be opened due to the continued heating of element 15, circuit for relay No. 1 will be opened and contacts 20, 21, 22 and 23 will be opened, thus de-activating ignition means and burner motor.

Under normal conditions, however, flame will 50 be produced at the end of a few seconds, and thermally controlled contact 40 will close, energizing coil 43 of relay No. 3 (see Figure 2). As a result of this energization, starting contact 9 for No. 1 relay will be opened, starting contact 45 for relay No. 2 will be closed, and relay No. 2 will be substantially immediately energized through the following circuit: 4, 5, 6, 7, W, R, 24, 56, 45, 51, 53, 21, 54, 55, heating coil 56 of the time switch, 57, coil 58 of relay No. 2, 59, 17^a to 4. Therefore, when flame is produced, relay 60 No. 3 is energized, and then substantially immediately thereafter relay No. 2 is energized, as well as heating coil 56 of the time switch.

With the closure of No. 2 relay, contact 60 of 65 a shunt circuit is closed by means of which the coil 15 of the thermal safety switch is shunted out or rendered inoperative, but the holding circuit for No. 1 relay is maintained. Also by closure of No. 2 relay, a holding contact 61 for 70 said relay is closed. Also motor contact 62 is closed so that when No. 1 relay opens, whereby in opening contact 22, the motor will not be de-energized.

The holding circuit for relay No. 1 does not 75 now include heating coil 15, but is now as fol-

lows: 4, 5, 6, 7, W, R, 24, 25, 20, 26, 12, 13, 14, 63, 60, 64, 16, 17^a to 4. It will be noted that this holding circuit for No. 1 passes through a contact 20 controlled by No. 1 as well as a contact 60 controlled by No. 2 relay.

The holding circuit for No. 2 relay is as follows: 4, 5, 6, 7, W, R, 24, 56, 45, 51, 61, 67, 55, 56, 57, coil 58, 59, 17^a to 4. It will be noted that this holding circuit passes through contact 45 of relay No. 3, contact 61 of relay No. 2 and heating 10 coil 56 of the time switch.

Flame is now produced, but ignition is still active and will remain active for a predetermined period of time as controlled by the time switch 12. This period corresponds to the time required 15 for the element 12 to move away from contact 13, after energization of heating coil 56, which resulted from energization of relay No. 2. It will be noted that the coil 56 is in both starting and holding circuits for relay No. 2, but the holding 20 circuit for No. 2 as a shunt, does not include contact 21 of relay No. 1. Therefore, when time switch contact 13 is broken and relay No. 1 and contact 21 open, coil 56 remains energized, as 25 long as flame is produced.

Continuing the operation:

All three relays are now energized, ignition and motor are energized, all contacts except the starting contact 9 for relay No. 1 are closed, and post-ignition energization will continue for 30 a predetermined period of time. The timing switch now moves to the right and at the end of a predetermined time for which it is set, contact 13 is broken, and No. 1 relay drops out, breaking its own holding contact 20, and starting contact 35 21 of No. 2 relay circuit, and opening the ignition and motor contacts which are controlled by relay No. 1. Ignition is thus de-activated, but motor operation continues.

Relays Nos. 2 and 3 (see Figure 3) are now 40 operative and the device is in what is known as the normal operative condition, that is heat is being delivered, and will be delivered until the thermostat element R breaks at W. It will be noted that until this break occurs the heating 45 coil of the time switch remains energized and the thermal element of the time switch remains in such a position that contacts 11 and 13 are open. This holding circuit for relay No. 2 has been previously traced.

After the call for heat has been satisfied, the opening at R—W renders the apparatus again 50 inoperative, closes the starting contact 9 for relay No. 1. However, it will be noted that no restart of the apparatus can take place until after 55 the predetermined time, required for the thermal element 12 of the time switch to move as the result of a cooling movement to the initial position, has transpired. At the end of this period, contacts 11 and 13 are again closed, thereby again 60 completing the starting circuit for relay No. 1, if contacts B, W, R, are making. This is a feature of the invention. This delayed return to starting position prevents re-ignition, in presence of residual and explosive material in the 65 combustion chamber.

In this embodiment of the invention, the thermal safety and time switches are in series in the starting circuit, which is energized on closure of the room thermostat. In case flame is obtained, 70 No. 3 relay pulls in and establishes a starting circuit for relay No. 2 (a feature) and No. 2 relay then closes and establishes its own holding circuit. Both holding and starting circuits of relay No. 2 pass through the contact 45 controlled by 75

No. 3 relay. The starting circuit for relay No. 2 is controlled by relay No. 1. The net result is that No. 2 relay cannot close unless relays No. 1 and No. 3 have previously closed. Therefore relay No. 2, which controls the burner motor or fuel feed during the normal running period, can be opened at any time after the ignition period, by relay No. 3 which opens as the result of flame failure, and therefore the burner can be immediately shut down at any time after the ignition period, as the result of flame failure. On the other hand, during ignition period the fuel feed apparatus is operatively maintained independently of relay No. 2 by relay No. 1, so that fuel and ignition can be supplied for a limited period of time whether or not flame is present.

The device of the present invention, therefore, provides means whereby ignition means is made operative before and after flame production. The device also provides means whereby there is a timed period between a shut down of the apparatus due to opening of relay No. 3, and re-energization of No. 1 relay. This delay safeguards against puffs or explosion due to the ignition of accumulated vapors, should the flame be extinguished prematurely or should the apparatus be stopped and started in quick succession, due to tampering with the room thermostat. An interval of approximately ninety seconds or more must elapse between the shut down of the burner apparatus, and reclosing of contacts 11-13 due to cooling motion of element 12.

It will also be noted that when relay No. 2 is energized the coil 15 of the thermal safety switch 6 is shunted out by contact 60, which is in the holding circuit of relay No. 1. It will further be noted that contact 40 must be open and therefore relay No. 3 must be de-energized and contact 9 closed before relay No. 1 can be energized. The starting circuit for relay No. 2 passes only through contact W of the room thermostat, and not through contact B.

An important feature is that contact 40 must be opened and therefore contact 9 closed, before the burner can start. This is important, because if the circuit to contact 40 should be shorted, either accidentally or intentionally, or should it stick and not open, it will be impossible for relay No. 3 to drop out, and therefore contact 9 cannot close and the burner apparatus cannot be started until after inspection and repair. This arrangement makes it necessary for the pyrostat contact 40 to check itself for safety after each operation.

Another important feature which is again referred to is the delayed closing of contacts 11 and 13 of the time switch due to the cooling motion of the thermal element of the switch. With this arrangement, ignition cannot be restarted, after flame extinguishment, except at the end of a time period of sufficient duration to allow dissipation of accumulated explosive fire-pot gases. Thus explosion is prevented. Moreover, if the flame should be extinguished prematurely with the burner in normal running position, the contact 40 will open de-energized coil 43 of relay No. 3 and thereby breaking contact 45 which will cause relay No. 2 to drop out and break the circuit to the burner motor by opening contact 62. Only a few seconds will elapse between the extinguishment of the flame and the opening of the burner motor circuit and any vapors generated in the meanwhile will have ample opportunity to escape from the combustion chamber before the time switch can close its contacts

11-13 to obtain a restart of the apparatus. Upon power failure after successful ignition, relays Nos. 2 and 3 will be de-energized. If power is resumed prior to the opening of pyrostat 40, relay No. 3 will be energized. Contact 9 will therefore be open, as well as contacts 11 and 13 and, therefore, relay No. 1 cannot be energized, to re-energize ignition and motor. A re-start cannot, therefore, be had until the pyrostat 40 has opened (to close contact 9) and until the thermostat 12 has cooled sufficiently to close contacts 11 and 13.

To recapitulate: After turning on the burner motor, and ignition simultaneously, the device operates to maintain ignition until flame is produced, and then to maintain ignition for an additional predetermined period, which is adjustable. In case of flame failure the present device shuts the burner apparatus down upon opening of the flame responsive device 40, which contact ordinarily opens at about ten seconds (very quick for a device of this kind). In devices of other types, the burner was not shut down until the thermal safety completed its timing period which was ordinarily one and one-half minutes as compared with ten seconds in the present device. After flame failure and shut down, the present control makes the burner to stand idle for a period sufficient for explosive gases to be drawn off by the natural draft of the furnace. In the present device this period is from one and one-half to two and one-half minutes. The thermostat is always in command of the burner apparatus to shut down whether it is being maintained in operative condition by relay No. 1 or relay No. 2 or by both relays.

I claim as my invention:

1. An apparatus for controlling combustion including as elements, an igniter and motor and means for controlling them for energization on a call for heat, means for independently controlling the motor to maintain its energization, thermal means responsive to production of combustion, means for timing an ignition period, and circuit connections and contacts so interconnecting the aforementioned elements that said combustion responsive means causes operation of said second named means to maintain motor energization and initiates timing action of the timing means after successful ignition, thereby to continue ignition energization during the timing period, said timing means at the end of a timing period effecting a de-activation of the first named means.

2. An apparatus for controlling combustion including as elements, an igniter and motor and means for controlling them for energization on a call for heat, means for independently controlling the motor to maintain its energization, thermal means responsive to production of combustion, means for timing an ignition period, and circuit connections and contacts so interconnecting the aforementioned elements that said combustion responsive means causes operation of said second named means to maintain motor energization and initiate timing action of the timing means after successful ignition, and continues ignition energization during the timing period, said timing means at the end of a timing period deenergizing said first named means to de-activate the igniter, while the second named means maintains motor energization, and said timing means at the end of the ignition timing period being maintained operative, and being constructed

to require a time period to return to inoperative position so as to prevent re-energization of the igniter after flame extinguishment, except at the end of a timed period.

5. 3. A device of the class described including an igniter, a fuel motor, a first relay operable when energized to energize the igniter and motor, and also to close first and second contacts, a second relay operable when energized to energize the 10 motor and also close a contact, a combustion responsive device operable in response to combustion to open a first and close a second contact, a thermal timer switch operable when heated to open first and second contacts, a heater for the 15 thermal timer switch, a starting circuit for the first relay including therein the first contact of the combustion responsive device and both contacts of the timer switch, a holding circuit for the first relay including therein the first contact of 20 the first relay and the second contact of said timer switch, a starting circuit for the second relay including therein the second contact of the combustion responsive device, the second contact of the first relay and the heater of the timer switch, and a holding circuit for said second relay including therein the second contact of said combustion responsive device, the contact of said 25 second relay, and said heater.

4. A device of the class described including an 30 igniter, a fuel motor, a first relay operable when energized to energize the igniter and motor and also to close first and second contacts, a second relay operable when energized to close a circuit to the motor and also close a contact, a combustion 35 responsive device operable in response to combustion to open a first and close a second contact, a thermal safety switch and heater therefor, a thermal timer switch operable when heated to open first and second contacts, a heater for 40 the timer switch, a starting circuit for the first relay including therein said safety switch, the first contact of the combustion responsive device, both contacts of the timer switch, and the heater of said safety switch, a holding circuit for the 45 first relay including therein said safety switch, the first contact of the first relay, the second contact of said timer switch, and the heater of said safety switch, a starting circuit for the second relay including therein said safety switch, the 50 second contact of the combustion responsive device, the second contact of the first relay and the heater of said timer switch, and a holding circuit for said second relay including therein the second contact of said combustion responsive device, 55 vice, the contact of said second relay, and said heater of the timer switch.

5. In a system of the class described including an igniter, a fuel motor, a first relay operable when energized to control igniter, and motor, a 60 second relay operable when energized to control the motor, a combustion responsive device operable only when flame is absent to permit energization of the first relay, and further operable only when flame is present to permit energization 65 of the second relay, a timer switch including a thermal element and a heater, a room thermostat, and circuit connections and contacts controlled by the room thermostat, timer switch, relays and combustion responsive device, and so 70 arranged that on initial closure of the room thermostat with said combustion responsive device in its inoperative position in absence of combustion the first relay is energized through a circuit which has been closed by the timer switch as 75 result of the cooling motion of the thermal element

to energize igniter and motor, and so that only after production of combustion and after said combustion responsive device moves to its operative position the second relay is energized to close a maintaining circuit for the motor, and the 5 heater is energized to cause the timer switch to open after a predetermined time period following successful combustion to de-energize the first relay and igniter, heater energization being maintained while the second relay is closed, so that on 10 combustion failure after successful combustion causing said combustion responsive device to return to inoperative position, the first relay can only be energized after a timed interval as a result of closing of the timer switch by cooling 15 motion of its thermal element.

6. In a system of the class described including an igniter, a fuel motor, a first relay operable when energized to control igniter and motor, a second relay operable when energized to control 20 the motor, a combustion responsive device, a timer switch and a heater for the timer switch, a room thermostat, and circuit connections and contacts controlled by the room thermostat, timer switch, relays and combustion responsive 25 device, and so arranged that on initial closure of the room thermostat and only in absence of combustion with said combustion responsive device in inoperative position, the first relay is energized through a circuit which has been closed by the 30 timer switch, and so that on production of combustion and after said combustion responsive device moves to its operative position, the second relay is energized, and also the heater for the timer switch, to cause the timer switch to open 35 after a predetermined time period to de-energize the first relay and igniter, and so that heater energization is maintained while the second relay is closed.

7. A device of the class described including an 40 igniter, a fuel motor, first electrically operable means operable when energized to control igniter and motor, second electrically operable means operable when energized to control the motor, a combustion responsive device, a thermal timer 45 switch and a heater for the timer switch, a room thermostat, and circuit connections and contacts controlled by the electrically operable means and combustion responsive device, timer switch and room thermostat, and so arranged that on initial 50 closure of the room thermostat and in absence of combustion with said combustion responsive device in inoperative position the motor and igniter controlling means is energized through a circuit which passes through the timer switch, 55 and so that only on production of combustion and after said combustion responsive device moves to its operative position, the second electrically operable means is energized to close a maintaining circuit for the motor, and also the heater is energized to cause the timer switch to open after a predetermined time period, to de-energize the first electrically operable means and igniter, and so that heater energization is maintained while the second electrically operable 65 means is energized.

8. A system of the class described, comprising, in combination, an electrical fuel supply controlling device, electrically controlled means for igniting the fuel supplied by said device, a first 70 switching mechanism in circuit with the fuel supply controlling device and electrically controlled ignition means, a relay for operating said switching mechanism, a second switch in a parallel circuit for the fuel supply controlling device, a 75

second relay for operating the second switch, an electrical timer, a timer switch, a main control, a circuit for the first relay including the timer switch and main control, a combustion responsive switch, and a circuit arrangement controlled by the main control and combustion responsive switch for simultaneously energizing the second relay and the electrical timer.

9. A system of the class described, comprising, in combination, an electrical fuel supply controlling device, electrically controlled means for igniting the fuel supplied by said device, a first switching mechanism in circuit with the fuel supply controlling device and electrically controlled ignition means, a relay for operating said switching mechanism, a second switch in a parallel circuit for the fuel supply controlling device, a second relay for operating the second switch, a thermostatic switch, an electric heating element therefor, a main control, a circuit for the first relay including the thermostatic switch and main control, a combustion responsive switch, and a circuit arrangement controlled by the main control and combustion responsive switch for simultaneously energizing the second relay and the electric heating element for the thermostatic switch.

10. A system of the class described, comprising, in combination, an electrical device for controlling the supply of fuel to a burner, electrically controlled ignition means for igniting the fuel supplied to the burner, switching mechanism in circuit with the fuel supply controlling device and ignition means, a first relay for operating said switching mechanism, a second switch in a parallel circuit for the fuel supply controlling device, a second relay for operating the second switch, an electro-thermal safety switch for rendering the entire system inoperative upon continued flow of current therethrough, a main control, an electrical timer, a timer operated switch, an energizing circuit for the first relay and electro-thermal safety switch including the main control, safety switch and timer operated switch, a combustion controlled switch, a circuit for the second relay and the electrical timer including the main control, safety switch and combustion controlled switch, and means controlled by the combustion controlled switch for preventing operation of the safety switch to render the system inoperative if combustion is successful.

11. A system of the class described, comprising, in combination, an electrical device for controlling the supply of fuel to a burner, electrically controlled ignition means for igniting the fuel supplied to the burner, switching mechanism in circuit with the fuel supply controlling device and ignition means, a first relay for operating said switching mechanism, a second switch in a parallel circuit for the fuel supply controlling device, a second relay for operating the second switch, an electro-thermal safety switch for rendering the entire system inoperative upon continued flow of current therethrough, a main control, a thermostatic timing switch, an electrical heater therefor, an energizing circuit for the first relay and electro-thermal safety switch including the main control, timing switch, and safety switch, a combustion responsive switch, a circuit for the second relay and the electrical heater including the main control, safety switch and combustion responsive switch and means controlled

by the combustion responsive switch for preventing operation of the safety switch to render the system inoperative if combustion is successful.

12. An oil burner control having a motor driven fuel-supply means, ignition means for said fuel-supply means, means for energizing said motor driven fuel-supply means, means for de-energizing said ignition system upon establishing combustion conditions and other means for rendering said ignition de-energizing means inoperative a predetermined period of time after combustion is established.

13. A control for a combustion heating device, having a fuel-supply means, an igniter for the fuel, a device for rendering said fuel-supply means and igniter operative to establish combustion and means for rendering said ignition inoperative a predetermined period of time after combustion is established.

14. An oil burner having a fuel-supply means, an ignition system therefor, means for controlling energization of said fuel-supply means to establish combustion, means for controlling energization of said ignition system, means for maintaining said fuel-supply means energized and for de-energizing said ignition system upon establishing combustion, and a time-delay means cooperating with said ignition system control means for maintaining said ignition system energized for a predetermined period after combustion is established.

15. An oil burner control means having a fuel-supply motor, an ignition system therefor, means for initiating operation of said motor and ignition system to establish combustion, a heat-responsive device for de-energizing said ignition system and maintaining said fuel-supply motor energized upon establishing combustion and time-delay means for rendering said heat-responsive device ineffective to de-energize said ignition system for a predetermined period after combustion is established.

16. An automatic control system for oil burners having an igniter comprising a thermal trip time switch arranged to de-energize said system, a heating coil for causing operation of said trip switch, a thermostat having contacts, a circuit for said heating coil closed responsive to actuation of said contacts, means in said circuit actuated responsive to actuation of said thermostat contacts for rendering operative said burner and igniter, means actuated responsive to combustion at the said burner for rendering said heating coil inoperative, a thermal time switch, a second heating coil for causing actuation of the contacts of said time switch and a circuit for said second time switch heating coil, means for operatively energizing said second heating coil circuit responsive to actuation of said combustion responsive means, said time switch being arranged to render said igniter operating means inoperative after a predetermined period.

17. In combination, an electrically operated fluid fuel burner having an electrically operable igniter, means for initiating operation of said burner and igniter, a timing device for stopping operation of said igniter and means responsive to the presence of a flame at said burner to start said timing device in operation to stop igniter activity a predetermined time after said flame responsive means has operated.

ERNEST M. MILLER.
